COMBINED HANDRAILING AND RAILING POST

Louis Blum and William J. Horgan, Jr., both of Pittsburgh, Pa., assignors to Blumcraft of Pittsburgh, Pittsburgh, Pa., a firm

Filed July 28, 1965, Ser. No. 86,324

Term of patent 14 years

(Cl. D13—7)

FIG. 1. FIG. 2. FIG. 3.

FIG. 1 is a perspective view illustrating the combined handrailing and railing post of our design;

FIG. 2 is an end view of the combined handrailing and railing post of our design;

FIG. 3 is a side view of the combined handrailing and railing post of our design.

The dominant features of the design are shown in solid lines.

The handrailing is broken away to indicate an article of indeterminate length.

We claim:

The ornamental design for a combined handrailing and railing post, as shown and described.
